Attest

UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC SWITCH.

Application filed July 10, 1919. Serial No. 309,854.

To all whom it may concern:

Be it known that I, GEORGE A. BURNHAM, a citizen of the United States, and resident of Saugus, in the county of Essex and State 5 of Massachusetts, have invented an Improvement in Electric Switches, of which the following is a specification.

My invention relates to electric switches and has more particular reference to an electric switch having a high current interrupting capacity.

The current interrupting capacity of an electric switch depends, among other things, upon the length of time during which the 15 arc persists upon the opening of the switch. The shorter this period, the higher may be the current interrupting capacity of the switch because of the shorter time during which the arc may act upon the oil and, by 20 its heat, vaporize it to thereby build up a gaseous pressure within the switch.

An object of my invention, therefore, is to provide means whereby the opening of the switch may be rapidly and quickly performed to thereby limit the duration of the 25 arc to but a short period.

A further object of my invention is to provide means whereby the opening movement of the switch is automatically accelerated 30 by the pressure developed within the switch caused by the interruption of the circuit controlled thereby.

The means whereby I accomplish these objects of my invention is by the provision 35 of a member associated with the switch operating mechanism operable to rapidly move said mechanism into open position upon the development of a pressure within said switch.

More specifically, the means comprises a 40 piston operable within a cylinder and communicating with the gas expansion chamber of the switch and connected through proper and preferably, speed-increasing, linkages 45 with the movable switch member. Upon the control of the switch by external means to open it and due to the pressure which may be consequently set up therein, said piston is actuated by such pressure to accelerate the 50 initial switch opening movement to thereby the more rapidly move the switch member into full open position thereby the more quickly to interrupt the circuit. By the provision of such means the interrupting ca-

pacity of a switch having certain physical 55 dimensions may be considerably increased.

Fig. 1 is a sectional elevation of an electric switch embodying my invention.

Fig. 2 is a plan view of the switch illustrated in Fig. 1.

Fig. 3 is a detail of the switch operating mechanism showing the relative positions of the operating component in the open position of the switch.

Fig. 4 is a detail illustrating the application 65 of my invention to a switch having a modified arrangement of switch operating mechanism.

As here shown, the switch with which my invention is associated includes the stationary switch members 10 secured in the switch frame 11 and the movable switch member including the brush member 12 supported on the end of the switch rod 13 passed through the bushing 14 of the switch 75 frame 11.

The switch operating mechanism is of the type arranged to move the brush member 12 in an approximately straight line and comprises the links 15 pivotally secured to the 80 yoke 16 from which the switch rod 13 is supported. Said links are pivoted at their other ends to the links 17 which are pivotally secured at their lower ends to the pin 18 secured in the switch frame. Guide links 85 19 are pivoted to said links 15 intermediate the ends thereof and at their free ends are pivoted to the lugs 20 formed on the switch frame. A bell crank lever, comprising the single arm 21 and the dual spaced-apart 90 arms 22, is pivoted on said pin or shaft 18 and said dual arms 22 are pivotally connected through the links 23 with said links 15.

The operation of said bell crank lever by external means serves to move said movable 95 switch member into closed or open position and said movable switch member is adapted to be locked in closed position by the alignment of said arms 22 of said lever and links 23. A slight movement of said bell crank 100 lever to break the toggle formed by said lever and said links 23 is sufficient to permit the weight of the movable switch member and associated mechanism to operate to move said movable switch member into full open 105 position.

The oil receptacle 25 is of more or less common construction and is removably se-

2
cured to the switch frame by the bolts 26 and wing-nuts 27. Oil is adapted to be contained in said receptacle in which the movable and stationary switch members are immersed and the space between the surface of the oil and the switch frame constitutes an expansion space for gas and vapor formed upon the operation of the switch.

In carrying out my invention for the automatic acceleration of the movable switch member into full open position, I provide a cylinder 30 which may be integral with the switch frame as shown or otherwise secured thereto and in communication with the expansion space within the switch. Said cylinder is open ended as shown. A piston 31 is slidably received within said cylinder and is a more or less tight fit therein. Said piston is adapted to be moved outwardly in its cylinder upon the building up of a pressure within the switch to accelerate the movement of the switch member into open position. For this purpose a connecting rod 32 is pivotally secured to said piston 31 as by a ball and socket connection 33 and is pivotally secured at its upper end to the double-armed lever 34 which is pivotally secured at 35 to the lugs 36 extended upwardly from the switch frame. The other end of said lever is pivotally connected at 37 to links 38 which are in turn connected at 39 to the switch operating levers 15.

Under normal conditions of switch operation in which but small pressure is developed within the switch, it is seen that the piston will be reciprocated within its cylinder by the movement of the switch operating mechanism without in itself acting in any appreciable degree upon said mechanism.

Upon the beginning of the interruption of a circuit having an abnormal value of current therein the arc formed between the movable and stationary switch members may cause an appreciable pressure to be set up within the switch. This pressure acts upon the piston 31 and causes it to be forced upward in its cylinder and consequently acting through the lever 34 upon the switch operating mechanism to rapidly move the movable switch member into full open position and thereby serving to quickly and rapidly interrupt the circuit. The greater the pressure set up within the switch, the greater will be the force acting upon the switch operating mechanism and the more quickly will the movable switch member be moved into open position and consequently the higher will be the current interrupting capacity of the switch.

In the modification shown in Fig. 4 the switch mechanism is entirely enclosed in the enclosing casing 40. The switch operating rod 13 of the movable switch member is pivotally connected at 41 to a guide link 42 which is pivotally connected at 43 to

the link 44 and said link is pivoted at 45 to a suitable support.

An operating link 46 is pivoted at 47 to said guide link 42 and extends on the other side of the switch operating rod and is pivoted at 48 to a suitable support on the switch. A bell crank lever 49 pivoted at 50 to the switch is connected to said operating link 47 through the link 51 and said bell crank lever and link 51 form a toggle by which the movable switch member is operated and restrained in closed position. The other arm of said bell crank lever is pivotally connected with an operating rod 52.

In this modification, the cylinder of the switch accelerating device is integrally formed with the casing 40. The piston 56 is slidably received therein and has a connecting rod 57 rigidly associated therewith and extended downwardly within said enclosing casing 40. Said rod has a pin therein which is received in the slot 58 of the lever 59 which is pivoted at 60 to a lug depending from said casing 40. The other end of said lever 59 is pivotally connected to a link 61 which is connected at 62 to said operating lever 46.

The operation of this device is identical with the operation of that shown in Fig. 1. Upon a pressure developed within the switch due to the opening of the switch, said piston 56 is moved upwardly to thereby depress the operating rod 13 and consequently the more rapidly to move the movable switch member to open position thereby the more quickly to interrupt the circuit.

It is obvious that many modifications of my invention may be made without departing from the spirit thereof.

I claim:—

1. An electric switch comprising stationary and movable switch members, and means to increase the speed of opening movement of the movable switch member for relatively high values of current arranged to be without material effect for relatively low values of current, said means comprising a casing adapted to contain a fluid in which the switch members are immersed and a substantial gas expansion space above the fluid, and a piston associated with the movable switch member to move it toward switch-open position and in communication with the gas expansion space and arranged to be effectively actuated by abnormal gaseous pressures within said space and be ineffective with small gaseous pressures within said space.

2. An electric switch comprising stationary and movable switch members, and means including a gas expansion space to increase the speed of opening movement of the movable switch member for relatively high values of current arranged to be without material effect for relatively low values of current.

3. An electric switch comprising the combination of an enclosing casing adapted to contain a fluid and a substantial gas expansion space above the fluid, stationary and movable switch members immersed in the fluid, switch-operating mechanism connected with the movable switch member, and a piston connected with said operating mechanism arranged in communication 10 with said gas expansion space to be effectively influenced only by abnormal gaseous pressures therein.

4. An electric switch comprising the combination of an enclosing casing adapted to

contain a fluid and a gas expansion space 15 above the fluid, stationary and movable switch members immersed in the fluid, and means to accelerate the switch-opening movement including a piston associated with said movable switch member and in communication with said gas expansion space. 20

In testimony whereof, I have signed my name to this specification, in the presence of two subscribing witnesses.

GEORGE A. BURNHAM.
